[57] CLAIM

The ornamental design for a chew toy for dogs, as shown.

DESCRIPTION

FIG. 1 is a top view of a chew toy for dogs showing my new design, the bottom view of such toy being a mirror image of said top view;

FIG. 2 is a side elevational view of one side of the chew toy shown in FIG. 1, the opposite side view of such toy being a mirror image of said side view; and,

FIG. 3 is an end view of the chew toy, the other end being a mirror image of said end view.
